CLAIM

The ornamental design for a framework structure for shelter, as shown and described.

DESCRIPTION

FIG. 1 is a front elevational view of a framework structure for shelter showing my new design.

FIG. 2 is a somewhat enlarged front elevational view of the joint part for framework structure thereof.

FIG. 3 is a top plan view of the joint part shown in FIG. 2.

FIG. 4 is a bottom plan view of the joint part shown in FIG. 2.

FIG. 5 is an end view of the joint part shown in FIG. 2.

FIG. 6 is a somewhat enlarged front elevational view of the connecting member thereof.

FIG. 7 is an end elevational view of the connecting member shown in FIG. 6.

FIG. 8 is a top plan view of the connecting member shown in FIG. 6.
